UNITED STATES PATENT OFFICE

WILLIAM T. COMER, OF ATLANTA, GEORGIA, ASSIGNOR TO CRYSTAL CARBONIC LABORATORY, OF ATLANTA, GEORGIA, A CORPORATION OF GEORGIA

BEVERAGE MIXING FAUCET

Application filed January 6, 1930. Serial No. 418,781.

The invention relates to beverage faucets and has as an object the provision of a faucet for drawing a definite quantity of syrup and carbonated water and agitating the materials together ready for consumption.

It is a further object of the invention to provide a faucet which will deliver a fixed quantity of syrup to each glass of the beverage.

10 It is a further object of the invention to provide a faucet which will automatically agitate the mixed syrup and carbonated water together so that it will be unnecessary to further stir the materials after drawing to 15 place the same in condition for drinking.

Further objects of the invention will appear from the following description when read in connection with the accompanying drawings showing an illustrative embodiment of the invention and wherein:

Fig. 1 is a central vertical section; and
Fig. 2 is a horizontal section on line 2—2 of Fig. 1 drawn to an enlarged scale.

As shown the device comprises a cylinder 10 having chambers 11, 12, 13 therein, the cylinder 13 being shown as adapted to be placed into communication with a reservoir 14 of syrup to be mixed with carbonated water as a beverage.

30 The chambers are shown as bounded by diaphragms 15, 16, 17, and 18, each having a port therein controlled by valve bodies 19, 20, 21, 22 respectively, said valve bodies being fixedly secured into a rod 23.

35 To conduct carbonated water to the chamber 11, there is shown a conduit 24 having a screwthreaded connection 25 which may have connected thereto a conduit leading to a carbonator of any usual form. The flow of carbonated water through the conduit 24 is 40 shown as controlled by means of a diaphragm 26 having a small opening 27.

For operation of the valves to draw a mixture of syrup and carbonated water, the rod 45 23 is shown as projecting below the lower end of cylinder 10 and may be provided with a ball 28 for contact with the bottom of a glass by means of which contact the rod 23 and the valve bodies may be lifted.

50 In normal condition prior to the drawing

of a glass of beverage, the rod 23 and the valve bodies are in the position shown in Fig. 1 wherein the ports in diaphragms 15, 16, and 18 are closed and that in diaphragm 17 is open and in this condition the chamber 12 will be filled with the desired quantity of syrup for a single glass of beverage as for instance one ounce, and also the chamber 11 will be filled with carbonated water under the pressure existing in the conduit 24 and the carbonator.

When a glass is placed under the lower end of cylinder 10 and the bottom of the glass brought into contact with the ball 28 and pressed upwardly, the rod 23 will be lifted thereby opening valves 19, 20, and 22 and closing valve 21 whereupon the carbonated water in the chamber 11 will flow into the glass and the syrup in chamber 12 will flow into chamber 11 and then into the glass with the carbonated water. At the same time chamber 13 will be filled from chamber 14 with an amount of syrup proper for the next succeeding glass.

70 The amount of carbonated water in chamber 11 is insufficient to fill the glass and carbonated water under pressure will flow through the small opening 27 to complete the filling of the glass and being under a considerable pressure will thoroughly stir the syrup with the water as it flows into the glass and after it has flowed thereinto until sufficient additional water has passed through the opening 27 to complete the filling of the glass.

When the glass is withdrawn the beverage will be found to be thoroughly mixed and carbonated ready for consumption without additional stirring.

85 The valve body 19 is larger than the valve body 20 and because of this fact the downward pressure upon rod 23 by the carbonated water entering through the opening 27 will overcome the upward pressure upon the valve 20 causing the valves to firmly seat in the positions shown in Fig. 1, and the chamber 11 will again be filled with water ready for 90 the next operation.

Also when the valves 19, 20, and 22 seat, valve 21 will open allowing the charge of syrup to flow from chamber 13 into chamber 100

12 thereby automatically measuring the syrup for each glass.

It will be understood that reservoir 14 may be removable from the cylinder for filling in any desired manner but in the form shown a lid 29 is shown hinged to the reservoir at 30 which may be opened and the reservoir filled by pouring syrup thereinto.

Minor changes may be made in the physical embodiment of the invention within the scope of the appended claims without departing from the spirit of the invention.

I claim:

1. A beverage dispensing faucet comprising, in combination, a cylindrical faucet body having aligned syrup measuring, syrup dispensing, and water chambers, each except the last having an outlet delivering to the next in the order named, means to control said outlets, the syrup measuring outlet being normally open and the remaining outlets normally closed, common means to actuate said controlling means to reverse their condition whereby to discharge syrup into the water chamber and the mixture from the water chamber outlet.

2. A beverage dispensing faucet comprising, in combination, a cylindrical faucet body comprising a syrup measuring chamber having an inlet opening, a syrup dispensing chamber and a water chamber each chamber having an outlet opening and the outlet of each except the water chamber opening into the next chamber in the order named, common means controlling said openings, the outlet of the measuring chamber normally in open condition and the remaining openings normally in closed condition, said common means operable to reverse such conditions.

3. A beverage dispensing faucet comprising, in combination, a cylindrical faucet body comprising a syrup measuring chamber having an inlet opening, a syrup dispensing chamber and a water chamber axially located in said body in the order named, each chamber having an outlet to the succeeding chamber and the outlet of the water chamber delivering from the faucet, a conduit for connection with a carbonator permanently open through a restricted passage into the water chamber, a rod extending axially through all of said chambers, valve bodies carried by said rod to control each of said openings, the outlet valve for the water chamber being larger than the inlet thereof whereby to hold said outlet normally closed and said valves so arranged as to normally close each of said openings except the outlet of the measuring chamber.

4. A beverage dispensing faucet comprising, in combination, a cylindrical faucet body having a syrup measuring chamber, a syrup dispensing chamber and a water chamber arranged vertically downwardly in the order named axially of the body, said body

extending below said water chamber to deliver fluid therefrom at the bottom of a receptacle telescoped with said extension, a valved inlet to the measuring chamber and valved outlets from the measuring, dispensing, and water chambers, each outlet except the last opening into the succeeding chamber and that from the last into said extension, said outlets aligned, a rod axial of the chambers and extending below said extension to be contacted by the inner surface of said telescoping receptacle bottom, valves carried by said rod controlling said valved openings with the outlet from the measuring chamber normally open and the remaining openings normally closed and a conduit to place said water chamber in continuous communication with a carbonator.

5. A beverage dispensing faucet comprising, in combination, a cylindrical substantially vertical faucet body having aligned syrup measuring, syrup dispensing, and water chambers each except the last having an outlet delivering to the next in the order named, means to control said outlets, the syrup measuring outlet being normally open and the remaining outlets normally closed, common means to actuate said controlling means to reverse their open or closed condition whereby to discharge syrup into the water chamber and the mixture of syrup and water from the water chamber outlet, said actuating means projecting below the faucet body for contact with the bottom of a receiving container telescoped over the body.
